REGENERATION OF SPENT ALKALI METAL
HYDROXIDE SOLUTIONS FROM REFINING
OF MINERAL OILSAmiot P. Hewlett, Cranford, N. J., assignor to
Standard Oil Development Company, a corpora-
tion of Delaware

Application March 15, 1941, Serial No. 383,502

5 Claims. (Cl. 23—184)

The present invention is concerned with the refining of mineral oils. The invention more particularly relates to an improved process for the regeneration of spent alkali metal hydroxide solutions utilized in the refining of petroleum oils. In accordance with the present process, spent alkali metal hydroxide solutions are regenerated utilizing an arrangement and sequence of stages wherein the spent solution is subjected to elevated temperatures and pressures in order to regenerate the same.

In the refining of oils, particularly in the refining of petroleum oils boiling in the motor fuel boiling range, it is desirable to remove the objectionable mercaptan compounds therefrom. This is usually accomplished by treating the oil with a so-called "doctor" solution comprising a saturated solution of lead oxide dissolved in sodium hydroxide. When the oil is treated with the doctor solution the mercaptan compounds are converted to soluble lead mercaptides. These compounds are then converted to alkyl disulfides by the addition of a reagent which usually comprises free sulfur. When free sulfur is employed the lead is precipitated as lead sulfide. This process for the removal of mercaptans is not entirely satisfactory since it is relatively difficult to add the correct amount of sulfur. If an insufficient amount of sulfur be added, soluble lead mercaptides remain dissolved in the oil, which compounds materially affect the burning qualities and the stability of the oil. On the other hand, if an excess of sulfur be added, the excess sulfur remains as free sulfur or in the form of organic polysulfides dissolved in the oil and is objectionable since it adversely affects the corrosiveness, gum stability, color stability and lead susceptibility of the oil. In view of this, various other processes have been suggested for the removal of the objectionable mercaptan compounds from oil. One process proposed is to contact the oil with an alkali metal hydroxide solution under conditions to convert the mercaptans to the corresponding alkali metal mercaptides, which constituents are removed with the spent alkali metal hydroxide solution. An operation of this character heretofore has not been entirely successful due to the fact that in order to remove the mercaptans to the desired extent, it has been necessary to employ a relatively large amount of the alkali metal hydroxide solution. Furthermore, the large amount of the mercaptide containing alkali metal hydroxide solution necessary was relatively difficult to regenerate which

prohibited its general acceptance as a commercial operation.

I have, however, now discovered a process by which the mercaptide containing alkali metal hydroxide solution secured in the removal of the mercaptans may be readily and efficiently regenerated so that it may be recycled to the treating zone. Furthermore, by recovering substantially all of the mercaptans from the caustic solution, the quantity of regenerated solution required is greatly reduced. In accordance with my invention, the mercaptide containing spent alkali metal hydroxide solution is regenerated by subjecting the same to elevated temperatures and pressures and the respective layers segregated under these conditions.

The process of my invention may be readily understood by reference to the drawing illustrating one modification of the same. For the purpose of description, it is assumed that the alkali metal hydroxide solution comprises a sodium hydroxide solution, and that the same is utilized for the removal of mercaptan compounds from a petroleum oil boiling in the motor fuel boiling range. The mercaptan containing petroleum oil is introduced into treating zone 1 by means of feed line 2. In treating zone 1 the oil is contacted with the sodium hydroxide solution which is introduced by means of line 3 under conditions to remove the mercaptan compounds from the oil. The treated oil free of objectionable mercaptan compounds is withdrawn from treating zone 1 by means of line 4 and handled or further refined in any manner desirable. The spent sodium hydroxide solution is withdrawn from treating zone 1 by means of line 5 and passed to storage zone 6. From storage zone 6 the spent sodium hydroxide solution is passed to heating zone 7 by means of line 8. In heating zone 7 the temperature of the spent sodium hydroxide solution is raised and the solution maintained under a pressure at least sufficient to maintain the solution in the liquid phase. The solution maintained under an elevated temperature and pressure is passed to settling zone 10 by means of line 9. In zone 10 the liquid solution is maintained at the elevated temperature and pressure for a sufficient time period in order to secure a separation between liquid mercaptans and the sodium hydroxide solution. The liquid mercaptans are withdrawn from settling zone 10 by means of line 11, cooled in cooler 12, passed through pressure release valve 13 and introduced into liquid mercaptan storage 14 by means of line 15. The partially regenerated caustic solution

is withdrawn from settling zone 10 by means of line 16, passed through pressure release valve 17, and introduced into flash zone 18. Temperature and pressure conditions are adjusted to remove overhead by means of line 19 residual quantities of mercaptans and water vapor which are condensed in condenser 21 and introduced into separation zone 20. Liquid mercaptans are withdrawn from separation zone 20 by means of line 22 while the water is withdrawn by means of line 23. The regenerated caustic solution is withdrawn from flash zone 18 by means of line 24, passed through cooling zone 25, and passed to regenerated sodium hydroxide solution storage 26 by means of line 27, from where it is recycled to treating zone 1 by means of line 3. Water or fresh sodium hydroxide solution may be introduced into zone 26 by means of line 28. Under certain conditions it may be desirable to introduce the spent heated caustic solution into flash zone 18 directly by means of line 29. This may be readily secured by adjusting valves 40, 41, 44, and 43.

The process of the present invention may be widely varied. The respective zones may comprise any suitable number and arrangement of units. Although the present process may be utilized for the regeneration of spent alkali metal hydroxide solutions utilized in the removal of mercaptan compounds from any oil, it is especially adapted for the regeneration of spent alkali metal hydroxide solutions, particularly sodium hydroxide solutions, utilized in the removal of mercaptan compounds from petroleum oils boiling in the motor fuel boiling range. These oils boil in the general range from about 100° F. to about 450° F.

The spent alkali metal hydroxide solution is heated to a temperature in the general range from about 300° F. to about 700° F. I have found that it is desirable to heat the solution to a temperature of at least 400° F. and that particularly desirable results are secured provided the solution be heated to about 500° F. The pressure at all times should be at least sufficient to maintain the constituents in the liquid phase. It is however preferred to employ pressures from about 25% to about 50% in excess of this figure.

The spent alkali metal hydroxide solution is subjected to the elevated temperature and pressure for a sufficient time period in a separation zone to secure a separation between liquid mercaptans and the sodium hydroxide solution. In general, I have found that this time period should be from about 10 to about 120 minutes, preferably from about 20 to about 40 minutes.

It has been found that the operation of appreciably improved and that the mercaptan removal can be facilitated by allowing some vaporization to take place from the top of the separation zone. If this operation be employed, a mixture of water vapor and vaporized mercaptans is removed by means of line 11, while liquid mercaptans are removed by means of line 30 and handled as described. The desired vaporization is controlled by adjusting the respective valves 31 and 42.

In order to illustrate the invention further, the following examples are given which should not be construed as limiting the same in any manner whatsoever:

Example 1

A spent sodium hydroxide solution utilized in removal of mercaptan compounds was separated

into a number of streams and the respective streams regenerated as described.

In one operation stream A was preheated to a temperature of about 212° F. and flashed into a flash zone in which the same was treated with stripping steam. In other operations, B to D, inclusive, the respective streams were handled at different temperatures in accordance with the process of the present invention. No venting from the top of the separation zone was employed. The results of these operations were as follows:

Operation	Temperature employed	Efficiency factor in the removal of mercaptans (utilizing operation A as a base)
A	212	100
B	300	123
C	400	176
D	500	320

From the above, it is apparent that the improvement in the removal of mercaptans which occurred by raising the temperature of the solution to 300° F. was not appreciable, but when the temperature of the solution was raised to 400° F., the improvement in the removal of the mercaptans had increased 76% and was more than tripled by raising the temperature of the solution to 500° F.

Example 2

In another operation, E, a spent sodium hydroxide solution secured as described with respect to Example 1 was regenerated at 400° F. which corresponds to operation C described in Example 1. In operation E vapors were withdrawn from the top of the pressure separating zone to the extent of 1.06 pounds of water per pound of sodium hydroxide in the solution added to the zone. The extent of the regeneration as measured by the efficiency factor and as compared to operation C is as follows:

Operation	Temperature employed	Efficiency factor in the removal of mercaptans (utilizing operation A as a base)
C	400	176
E	400	320

From the above it is apparent that unexpected desirable results are secured in accordance with the present process, particularly when allowing a small amount of vaporization to occur to the top of the separation zone.

What I claim as new and wish to protect by Letters Patent is:

1. Process for the regeneration of spent alkali metal hydroxide solution secured in the removal of mercaptan compounds from petroleum oils, which comprises heating the spent alkali metal hydroxide solution to a temperature in the range from about 300° F. to about 700° F., and maintaining a pressure on the heated solution substantially equivalent to the vapor pressure of the solution, whereby a liquid mercaptan phase and an alkali metal hydroxide solution phase form, then separating the mercaptan phase.

2. Process as defined by claim 1, in which the temperature is in the range from about 400° F. to about 700° F., and in which the pressure is regulated in a manner that a relatively small amount of the mercaptans are vaporized, separating the vaporized mercaptans, and separating a liquid layer of mercaptans.

3. Process for the regeneration of a spent alkali metal hydroxide solution utilized in the removal of mercaptans from petroleum oils, which comprises heating the spent alkali metal hydroxide solution in an initial stage to a temperature in the range from about 300° F. to about 700° F., and maintaining a pressure on the solution substantially equivalent to the vapor pressure of the solution, whereby a liquid mercaptan phase and an alkali metal hydroxide solution phase form, separating the mercaptan phase, re-

moving the partially regenerated alkali metal hydroxide solution and flashing the same in a secondary stage by substantially reducing the pressure whereby the remaining mercaptan compounds are removed from said solution.

4. Process as defined by claim 3, in which said alkali metal hydroxide solution is heated to a temperature in the range from about 400° F. to 700° F.

10 5. Process as defined by claim 3, in which the pressure maintained in said initial stage is adjusted to permit vaporization of a relatively small amount of the total mercaptans, which vaporized mercaptan fraction is subsequently combined with the liquid fraction removed from the spent alkali metal hydroxide solution in said initial stage.
